Primary Examiner — Rhea Shields

(57) **CLAIM**

The ornamental design for cartridge for coffee machines, as shown and described.

DESCRIPTION

1.-2. Cartridges for coffee machines

1.1 : Top

1.2 : Front

1.3 : Bottom

1.4 : Perspective

2.1 : Top

2.2 : Front

2.3 : Bottom

2.4 : Perspective

2.5 : Front view with dotted hidden parts

Two designs of capsules to be used in beverage preparation machines to produce beverages by passing hot water through a substance contained in the capsule; for both designs the back, right and left views are identical to the front view; In the reproductions, the broken lines are for the purpose of illustrating environment only and form no part of the claimed design.

1 Claim, 9 Drawing Sheets(56)
